CENTRIFUGAL CLUTCH FOR SPINDLES

Chalmers H. White, Greensboro, N. C.

Application March 22, 1950, Serial No. 151,063

1 Claim. (Cl. 242—46.5)

1

This invention relates to spindles of a type such as are used on spinning frames, twisting frames, and the like, and more especially to a centrifugal clutch adapted to be associated with a spindle on which a bobbin or tube is adapted to be mounted and for securing the tube on the spindle upon rotation thereof.

It is well known, to those familiar with the art, that the majority of wooden bobbins and all paper tube bobbins are secured on the spindle blade or cone let-on of a spindle by a tapered fit in order that upon rotation of the spindle blade, like rotation will be imparted to the bobbin or tube carried thereby. However, upon a doffing operation, it is the usual practice for an operator to grasp the bobbin to stop rotation thereof and to then lift the bobbin or paper tube off the blade. In many instances, the paper tube or bobbin may stick to the cone let-on or the blade, as the case may be, to such an extent that it is necessary to stop the spinning frame and to strike the lower end of the bobbin or paper tube with a blunt instrument in order to remove the bobbin or tube from the spindle.

It is, therefore, an object of this invention to provide an improved means for mounting the paper tube or wood bobbin, as the case may be, on the rotatable portion of a spindle, such as the blade or cone let-on, in such a manner that a tapered fit between the paper tube and the blade of the spindle is unnecessary and including means for frictionally engaging the interior of the paper tube adjacent its upper end upon rotation being imparted to the rotatable portion of the spindle so as to transmit like rotation to the paper tube. On the other hand, immediately upon cessation of rotation of the rotatable portion of the spindle, the means on the rotatable portion of the spindle engaging the interior of the paper tube will be relaxed to thus permit the tube to be easily removed from the blade.

Another object of this invention is to provide an improved spindle for spinning frames and the like comprising a fixed bolster case adapted to be secured to the bolster rail of the spinning frame and having a rotatable blade mounted thereon provided with a centrifugal clutch adjacent the upper free end thereof. This centrifugal clutch is provided with means for collapsing or contracting the same when the blade is stationary so that a paper tube or bobbin may be freely mounted on the blade, and upon rotation being imparted to the blade, the centrifugal clutch will expand and engage the interior of the paper tube adjacent the upper end thereof so as to impart

2

like rotation to the paper tube. Upon stopping rotation of the blade for doffing purposes, the centrifugal clutch again contracts thus permitting freedom of movement of the paper tube in removing the same from the blade.

There are many spindles in use which are provided with a rotatable whorl having a blade projecting upwardly therefrom and the whorl has a tapered portion, usually termed a cone let-on, integral with and also projecting upwardly therefrom and surrounding the lower portion of the blade and this tapered portion of the whorl is adapted to receive the internally tapered lower end of a wood bobbin. Many plants which have been using this type of wood bobbin may desire to change to the use of paper tubes, the internal diameter of which is substantially greater than that of the wood bobbin.

It is, therefore, another object of this invention to provide first and second adapters which may be mounted on the whorl and blade, respectively, of the type spindle previously described, the first adapter being adapted to fit over the upwardly projecting tapered portion of the whorl to provide a shoulder for supporting the lower end of the paper tube and the second adapter being provided with a centrifugal clutch of the type heretofore described and being adapted to be mounted on the upper end of the relatively small blade for holding the paper tube of relatively larger internal diameter on the blade on which the second adapter is mounted.

Some of the objects of the invention having been stated, other objects will appear as the description proceeds when taken in connection with the accompanying drawings in which:

Figure 1 is an elevation of the improved spindle with parts broken away and showing the same mounted on a portion of a bolster rail and also showing a paper tube type of bobbin mounted thereon;

Figure 2 is an enlarged sectional plan view of the centrifugal clutch taken substantially along the line 2—2 of Figure 1 and showing the clutch in contracted position;

Figure 3 is a view similar to Figure 2 but showing the centrifugal clutch in expanded position.

Figure 4 is an enlarged fragmentary vertical sectional view through the upper end of the spindle taken substantially along the line 4—4 in Figure 1 and showing the centrifugal clutch in contracted position;

Figure 5 is an elevation similar to Figure 1 but showing a modified form of the invention and including the adapters for increasing the size of

a spindle of the type usually employed in association with a wood bobbin and one of the adapters including a clutch of the type shown in the original form of the invention.

Figure 6 is an enlarged vertical sectional view taken through Figure 5 but showing only the adapters and the paper tube bobbin in cross section, the bolster, whorl and blade of the spindle being shown in elevation.

Referring more specifically to the drawings, the numeral 10 designates a spindle of a type such as is used on spinning frames, twisters and the like and which comprises a bolster case 11 which slidably penetrates a bolster rail 12, only a portion of which is shown in cross section in Figures 1 and 5. The bolster case 11 is secured in the bolster rail 12 by a lock washer 13 and a nut 14, the bolster case 11 having an enlarged annular portion 15 integral therewith which is secured against the upper surface of the bolster rail 12 by the nut 14 being threadably mounted on the bolster case 11. The spindle 10 is provided with a suitable L-shaped doffer guard holder 16 having a doffer guard 17 mounted for sliding movement therein, this doffer guard 17 being adapted to move out of the vertical plane of a whorl 20 for removing the whorl and its blade 21 from the bolster 11. The doffer guard 17 is provided to restrict upward movement of the whorl 20 in the event of a bobbin sticking to a blade 21 upon being removed therefrom.

The whorl 20 and the blade 21 constitute parts of the present invention. The manner of mounting the blade 21 in the whorl 20 and in the bolster case 11 with respect to each other is conventional and an illustration or description thereof is deemed unnecessary.

The whorl 20 is conventional with the exception that it is provided with an enlarged portion 22 to form a shoulder 23 at its juncture with the lower portion of the blade 21. The purpose of this shoulder 23 is to support the lower end of a bobbin, such as a paper tube bobbin 25 shown in Figure 1. Since most paper tubes are substantially the same length, by supporting the lower ends of the tubes 25 on a shoulder 23 disposed the same distance above the whorl on a plurality of spindles of the type shown in Figure 1, it is thus seen that the tube 25 on each of a plurality of spindles will be disposed at the same elevation thus insuring that the yarn wound onto the paper tube bobbins 25 will be distributed over a similar area of each of the paper tube bobbins 25.

It will be noted in Figure 1 that the blade 21 is tapered substantially its entire length, this taper being greater per foot than the internal taper of the paper tube bobbin 25. The conventional paper tube bobbin 25 has a metallic ferrule 26 at the lower end thereof and a similar ferrule 27 at the upper end thereof, the ferrule 27 restricting the upper end of the tube 25. The blade 21 has an enlarged portion 30 at the upper end thereof, which, although it is larger than the upper end of the tapered portion of the blade 21, is of substantially less diameter than the lower end of the tapered portion of the blade 21. This enlarged portion 30 carries a centrifugal clutch broadly designated at 32. The centrifugal clutch 32 comprises a plurality of segmental clutch shoes 34 which are shown to be quadrants in Figures 2 and 3 but which may be made in any number of parts of a circle.

The blade 21 has a restricted portion 35 integral therewith and disposed immediately above the enlarged portion 30 and an enlarged upper

portion 37, of substantially the same diameter as the enlarged portion 30 is provided which is also an integral part of blade 21 and the portions 30 and 37 are spaced apart from each other adjacent opposed ends of the restricted portion 35 thus forming a circumferential groove in which the clutch segments 34 have sliding movement. The restricted portion 35 of the blade 21 between the enlarged portions 30 and 37 is provided with a plurality of equally spaced radially extending bores 40 in which guide pins 41 have radial sliding movement.

Each of the pins 41 is provided with a restricted portion 42 to the outer end of which the corresponding clutch shoe 34 is secured by any suitable means such as a screw 43. Each of the segments 34 is provided with a groove 45 in the outer surface thereof, the grooves 45 in the shoes 34 coinciding to form a peripheral groove around the assembled segments 34 in which an endless coiled spring 46 is mounted. This coiled spring 46 tends to urge the segments 34 against semicircular strap members or travel limit bands 48 and 49 which are secured to the restricted portion 35 of the blade 21 by any suitable means such as screws 50. These semicircular members 48 and 49 are slidably penetrated by the restricted portion 42 of the guide pins 41 and are provided to restrict outward movement of the clutch shoes 34 by virtue of the shoulder formed by the enlarged portions 41 engaging the inner surface of the corresponding semicircular members 48 or 49 in the event of rotation being imparted to the blade 21 in the absence of a tube or bobbin encircling the blade 21.

It is evident that, upon a bobbin such as the paper tube 25 being placed over the blade 21 as shown in Figures 1, 2 and 4, the blade 21 would be stationary and the clutch shoes 34 would be in the position shown in Figure 2. However, upon rotation being imparted to the blade 21, the clutch shoes 34 will move to the expanded position shown in Figure 3 by centrifugal force and will engage the interior surface of the tube 25 to frictionally hold the tube 25 so that rotation of the blade 21 will cause like rotation to be transmitted to the tube 25.

Referring to Figure 5 there is shown a spindle designated at 60 and the structure of the bolster case thereof is identical to the bolster case 11 and associated parts shown in Figure 1. The parts of the spindle 60 which are identical to those of the spindle 10 will bear the same reference characters with the prime notation added.

The spindle 60, in Figure 5, has a conventional whorl 20' and a conventional tapered blade 21' mounted for rotation in the usual manner thereon, the whorl 20' being provided with a tapered upwardly extending cone let-on portion 61, and it will be observed that the blade 21' in Figure 5 is substantially smaller relative to the tube 25' than the blade 21, in Figure 1, relative to the tube 25, the tapered cone let-on portion 61 of the whorl 20' and the blade 21', in Figure 5, being of a size relative to the tube 25' usually provided for reception of a wood bobbin or for a substantially smaller tube than that shown in Figure 1 and 5.

Heretofore, in order to use a tube of the comparative size shown in Figures 1 and 5, it has been necessary to replace the blade 21 and the whorl 20 with a similar blade and whorl having a larger diameter and, in which event, the lower end of the tube would frictionally engage the tapered portion 61 of the whorl 20'. Now, in order that the blade 21' and the whorl 20' may be used with

a tube of the comparative size shown in Figure 5, there is provided a whorl adapter broadly designated at 65 and a blade adapted broadly designated at 66, the configuration of the interior of the whorl adapter 65 being substantially the same as the configuration of the exterior of the upper portion of the whorl 20' in Figure 5 so as to provide a tapered fit between the adapter 65 and the cone let-on 61.

The whorl adapter 65 comprises an annular base portion and a restricted portion 70, the diameter of the restricted portion 70 being less than the internal diameter of the lower end of the paper tube bobbin 25' so that this portion 70 merely serves to position the lower end of the paper tube bobbin 25'. The whorl adapter 65 is provided with a tapering upper portion 71 to assist in positioning the lower end of the paper tube bobbin 25' on the whorl adapter 65, the annular portion 67 serving to support the lower end of the paper tube bobbin 25'.

It is well known, by those familiar with the art, that the blade 21' of a spindle of this type is tapered, gradually increasing in diameter from the top to the bottom thereof, and the blade adapter 66 has a tapered longitudinally extending bore 74 therein which is tapered to provide a tapered fit between the blade adapter 66 and the blade 21'. The upper end of the blade adapter 66 is identical in structure to the upper end of the blade 21 shown in Figure 1 and those parts in Figure 5 which are identical to the parts shown in Figure 1 shall bear the same reference characters with the prime notation added and a further description thereof is deemed unnecessary.

It is thus seen that I have provided an improved spindle for spinning frames and the like including a centrifugal clutch in the upper portion of the blade thereof and providing means whereby a paper tube bobbin or bobbin of similar internal dimensions may easily be placed on or withdrawn from the blade and, upon rotation being imparted to the blade, the centrifugal clutch will be effective in holding the paper tube bobbin so that like rotation will be imparted thereto.

The fact that the centrifugal clutch 32 is disposed closely adjacent the upper end of the blade 21 in Figure 1, or above the blade 21' in Figure 5, will insure that the clutch shoes 32 will engage the bobbin 25 adjacent the upper end there-

of and will thus minimize the possibility of the bobbin 25 flying off the upper end of the blade 21, or the blade adapter 66 in Figure 5 upon rotation being imparted thereto.

In the drawings and specification there has been set forth a preferred embodiment of the invention and although specific terms are employed they are used in a generic and descriptive sense only and not for purposes of limitation, the scope of the invention being defined in the claim.

I claim:

An improvement in a centrifugal clutch for a spindle having a blade adapted to carry bobbins for spinning frames and the like, said clutch characterized by said blade having a reduced portion intermediate its ends defining a circumferential groove and having a plurality of circularly arranged segmental clutch shoes slidably mounted in the circumferential groove and also having resilient means normally urging the segmental clutch members towards the axis of the spindle, said improvement comprising a corresponding pin for each of the segmental clutch members mounted for radial sliding movement in the reduced portion of the blade, a relatively thin annular band secured to the periphery of said reduced portion, each of said pins having a reduced outer end portion slidably penetrating said band and means securing the segmental members to the reduced outer end portions of the corresponding pins whereby rotation of the spindle will cause the segmental members to move outwardly and frictionally engage the interior surface of the bobbin to thereby impart like rotation to the bobbin from the blade.

CHALMERS H. WHITE.
